ADJUSTABLE SWITCH ADAPTER BRACKET

Fred W. Buckman, 943½ Agate,
San Diego, Calif. 92109

Filed May 7, 1971, Ser. No. 141,458

Term of patent 14 years

Int. Cl. D8—08

U.S. Cl. D8—233

Fig. 1

Fig. 2

Fig. 3

Fig. 4

FIG. 1 is a perspective view of an adjustable switch adapter bracket, showing my new design.

FIG. 2 is an underside view thereof.

FIG. 3 is a side elevational view of the bracket as shown in FIG. 2.

FIG. 4 is a perspective view of the bracket adjusted to a different position.

I claim:

The ornamental design for an adjustable switch adapter bracket, substantially as shown.
